HAND BAG

Harry D. Gihon, 3d, Trenton, N. J., assignor to
Atlantic Products Corporation, Trenton, N. J.,
a corporation of New Jersey

Application February 21, 1933, Serial No. 657,758

2 Claims. (Cl. 190—41)

This invention relates to luggage and pertains more particularly to handbags having an opening adapted to be closed by a separable fastener, preferably of the slide fastener type.

6 Handbags of this type have recently attained great popularity because of their light, rigid construction, and they are used extensively by persons engaged in athletic pursuits for carrying athletic equipment, etc. Because of their relatively small size, however, it has been impossible to enclose some articles such as tennis or squash racquets which it is frequently desirable to carry from place to place. It is an object of the present invention to so construct a handbag that such 15 articles may be conveniently carried therein.

Other objects and advantages of the invention will appear hereinafter.

A preferred embodiment of the invention selected for purposes of illustration is shown in the 20 accompanying drawing, in which,

Figure 1 is a perspective view of the handbag in condition for ordinary use.

Figure 2 is a similar view showing a racquet enclosed.

25 Figure 3 is an enlarged detail view of the handle opening.

Referring to the drawing, the handbag illustrated comprises side members 1 and 2, connected to the bottom member 3 and to gusset member 30 4 in any suitable manner.

In the preferred embodiment illustrated the gusset member is provided with a longitudinal opening, the opposed edges of which are supplied with intermeshing parts 6 and 7 of a slide fastener which serves as a closure member for the bag. At one end of the bag, closely adjacent the point where the gusset member is attached to the bottom of the bag the gusset member is cut away to provide a substantially circular opening 8 of a size to receive the handle 9 of a racquet as illustrated in Figure 2. If desired, the edges of the opening 8 may be faced with a covering 10 of leather or other suitable material. As will be observed the parts 6 and 7 of the slide fastener 40 are carried to the edge of the circular opening in order that when the slide 11 is moved to close the bag it may hold the edges of the opening 8 snugly about the handle 9, and when the slide 11 is moved to open the bag, the gusset members 50 are permitted to separate all the way to the bottom of the bag so that the handle may be easily inserted and withdrawn therefrom.

As illustrated in Figure 2, the above described construction permits the insertion of a racquet

in the bag in such manner that it may lie flat on the bottom of the bag with the handle projecting through the opening 8. If desired, a pocket 12 may be provided to enclose the stringed part 60 of the racquet, in order to hold it in place and in order to separate it from the remaining contents of the bag. The pocket may be closed with snap fasteners 13 if desired.

In order that the bag may be used for ordinary purposes when desired, a patch 14 may be supplied which may be connected to the bag at any suitable point by a leather thong 15. This patch is of a size to cover the opening 8, and may be held in place by snap fasteners 16.

It will be understood that the invention may 70 be variously modified and embodied within the scope of the subjoined claims.

I claim as my invention:

1. A handbag comprising a pair of side members, a bottom member secured thereto, a gusset member secured to the side and bottom members, said gusset member being provided with a longitudinal opening, interlocking members of a slide fastener secured to the free edges of said opening, a second opening in said gusset member 75 located close to the bottom and at one end of said longitudinal opening and communicating therewith, said interlocking members extending the entire length of said longitudinal opening but ending at said second opening, so that said 80 second opening is not closed thereby.

2. A handbag comprising a pair of side members, a bottom member secured thereto, a gusset member secured to the side and bottom members, said gusset member being provided with a longitudinal opening, interlocking members of a slide fastener secured to the free edges of said opening, a second opening in said gusset member 90 located close to the bottom and at one end of said longitudinal opening and communicating therewith, said interlocking members extending the entire length of said longitudinal opening but ending at said second opening, so that said second opening is not closed thereby, and a pocket 95 secured to the bottom of the bag at the end of the bag remote from said second opening, said pocket having its open side facing said second opening.

HARRY D. GIHON, 3RD.
